UNITED STATES PATENT OFFICE.

ANTOINE ANDRÉANI, OF GENEVA, SWITZERLAND.

SAFETY DEVICE FOR LOCKS.

1,360,489.

Specification of Letters Patent. Patented Nov. 30, 1920.

Application filed July 30, 1919. Serial No. 314,360.

To all whom it may concern:

Be it known that I, ANTOINE ANDRÉANI, a subject of the Kingdom of Italy, residing at Geneva, Switzerland, have invented new and 5 useful Improvements in Safety Devices for Locks, of which the following is a specification.

The subject of the present invention is a safety device for locks which comprises, 10 similarly to other known safety devices, a rotatable cylinder held by tumbler elements which may be displaced by a key to release the cylinder and permit its rotation. The invention is distinguished by the fact that 15 the tumbler elements act in two diametrically opposite positions of the cylinder and by the fact that the cylinder is released by the withdrawal of the tumbler elements into the cylinder in lieu of by pushing them out- 20 ward.

The accompanying drawings show two embodiments of the invention, Figure 1 being a longitudinal section of one embodiment applied to a strong box lock. Fig. 2 is 25 an end view of the same. Fig. 3 is a longitudinal section of a second embodiment applied to a door, Fig. 4 is a front view thereof, Figs. 5 and 6 show the key of the device shown in Fig. 1 in side view and in section 30 on the line x . y . Figs. 7 and 8 show in front view and in section a group of two tumbler elements in locking position. Figs. 9 and 10 show the same in unlocking position.

The embodiments shown comprise—

35 (1st) A casing t traversed by a cylindrical opening and within which are formed two diametrically opposite longitudinal grooves a . a . This casing is secured to the door or to the lock.

40 (2nd) A rotatable cylinder o exactly fitted in the opening of the casing t and traversed by a longitudinal groove b corresponding to the grooves a . a .

(3rd) Two series of plates c . d . disposed 45 alternately in the groove b of the cylinder and forming tumbler elements. The ends of these plates engaged in the grooves a . a . under the action of springs e , Figs. 7 and 8, may be freed as will be seen hereinafter, by 50 the action of the key.

(4th) A key Figs. 5 and 6 having an H-shaped section, the two parallel sides f of which are rectilinear while the cross member g is waved irregularly throughout its length.

55 The side members terminate in a beveled end

h which permits their introduction into the device.

The plates c Figs. 7 to 10 are provided with rectangular openings forming at their lower end a projecting tongue u intended to rest on the waved portion of the key. The plates d are similarly shaped save that the tongue u is at the upper end.

In the inoperative position of the device, 65 Figs. 7 and 8, the superposed tongues u leave two small openings i . i . which prevent fraudulent attempts to operate the lock. In this position the plates engaged in the grooves a under the action of the springs e prevent 70 any movement of the cylinder o . If the key is then introduced by causing the sides to move into the openings i . i . the inclined surfaces of the key end draw the plates into the cylinder forming a passage for the waved 75 portion against which the tongues u then bear. The plates are then more or less displaced according to the part of the waved cross member on which they rest and they are provided with an opening and a tongue 80 in order that when the key is completely pushed in, Figs. 1 and 3, they may be all disengaged from their groove. The cylinder may then be turned, which by an external extension j or by any suitable arrangement 85 actuates the bolt, locks or other closing members. The key, Figs. 5 and 6, is provided along one of its sides with a longitudinal groove m corresponding to a projection n , Figs. 2 and 4, so as to prevent it being presented incorrectly to the device.

Each plate being formed with an opening and tongue to occupy a certain position in the cylinder and to correspond to a key of certain form, the slightest variation in the 90 waved portion of the key will have for effect to leave one or more plates in engagement with one or other of the grooves a and prevent the lock from being opened.

The device may be such as to allow the use 100 of master keys. Figs. 1 to 4 show one example thereof. Fig. 1 shows a device fixed to the door p of a strong-box and comprising eight pairs of plates, the key being shown in full position ready to operate. Fig. 3 shows a device fixed to the lock s of a door and comprising only three pairs of plates similar to those at the inner end of the device shown in Fig. 1. It is clear that the key of Fig. 1 will open this door if only the outer end 110 portion of the waved part is used, but a

special key may also be provided which is shorter and includes only this end portion which will open the door yet cannot open the strong box. Thus there may be a series 5 of devices comprising from two to seven pairs of plates with reduced keys adapted to actuate only the number of plates for which they are made and numbers less than that.

10 Having now particularly described and ascertained the nature of my said invention and in what manner the same is to be performed I declare that what I claim is:—

A safety device for locks, comprising in 15 combination, a casing provided with a plurality of oppositely disposed longitudinal grooves, a cylinder rotatable in said casing and having a plurality of alternately disposed spring-pressed slidable plates normally projecting into a pair of said grooves 20

at diametrically opposite sides of the casing, each of said plates being provided with an opening and a projecting tongue in said opening, the tongues of alternate plates being adapted to overlap each other when in 25 locking position thereby to leave a small opening at each side of the overlapped tongue, and a key of H-shape in cross section the extreme ends thereof being beveled to permit their insertion into said small 30 openings, said key also having between its sides a pair of undulating ribs adapted to contact with said tongues thereby to withdraw the plates into unlocking position.

In testimony whereof I have signed my 35 name to this specification.

ANTOINE ANDRÉANI.
